UNITED STATES PATENT OFFICE.

CHARLES LE DUC, OF VERNAL, UTAH.

WATER-WHEEL.

1,320,626.

Specification of Letters Patent.

Patented Nov. 4, 1919.

Application filed April 4, 1919. Serial No. 287,492.

To all whom it may concern:

Be it known that I, CHARLES LE DUC, a citizen of the United States, residing at Vernal, in the county of Uintah, State of Utah, have invented certain new and useful Improvements in Water-Wheels; and I do hereby declare the following to be a full, clear, and exact description of the invention, such as will enable others skilled in the art 10 to which it appertains to make and use the same.

This invention relates to new and useful improvements in motors and particularly to water motors.

15 One object of the present invention is to provide a novel and improved structure which is of the rotary type and which is adapted to be operated by the weight of the water, rather than by the force of the 20 stream, thus deriving the maximum of power from the amount of water consumed.

Another object is to provide a novel and improved device of this character wherein friction is reduced to a minimum and the 25 motor driven at a comparatively slow but constant speed and capable of developing great power.

Other objects and advantages will be apparent from the following description when 30 taken in connection with the accompanying drawings:

In the drawings:

Figure 1 is a side elevation of a motor made in accordance with my invention.

35 Fig. 2 is an edge view thereof.

Fig. 3 is a vertical sectional view taken on the line 3—3 of Fig. 2.

Fig. 4 is a horizontal sectional view taken on the line 4—4 of Fig. 1.

40 Fig. 5 is an enlarged vertical sectional view taken on the line 5—5 of Fig. 1, showing the arrangement of the lug 30' and pin 29'.

Referring particularly to the accompanying drawings, 11 represents a base on which 45 is formed the upwardly extending casing 10. This casing has the side walls 10' which define a curved channel 16 for the water wheel which will later be described. Also 50 formed on the base are the upwardly extending supports 12, and mounted on the upper end of each of the supports is an L-shaped member 29 having a screw 30 in the vertical portion thereof. A bearing 55 block 13 is disposed on the horizontal portion of the member 29 and has a slotted ex-

tension 31 through which a retaining bolt 32 is disposed and engaged in the said horizontal portion of the member 29. The inner end of the screw 30 bears against the adjacent side of the bearing block 13 whereby the said block can be slidably adjusted on the member 29. Journaled at its ends in the bearing blocks 13 is the shaft or axle 14 which carries the water wheel 21. This 65 wheel has the parallel peripheral flanges 24 which engage in the channel 16 of the casing. In the periphery of the body 21' of the wheel there are formed the recesses 23, and pivotally mounted in each of said recesses is the blade 26. The shaft 27' of each blade is turned at right angles to the shaft, at one end, as shown at 27, while the other end is turned at right angles to the shaft but in a plane at right angles to the end 27. 70 In the peripheral face of the body 21' of the wheel, and at one side of the recess, there is formed a groove 28' for the reception of one end of the blade, so that the blade, when feathered, will lie flush with the peripheral 75 face of the body. Formed on the casing, and opposite the grooved portion thereof, is a curved guide 33, which is disposed in concentric relation to the shaft 14, and in which is formed a channel or groove 34 for the 80 reception of the ends 28 of the shafts 27'. On the upper end of the casing, and depending from one side thereof, is a lug 30' which carries a horizontally disposed pin 29', 85 against which the ends 27 of the shafts 27' engage, successively, as the wheel rotates, and by means of which the blades are turned to extend into the groove 16 and receive the flow of water thereagainst. A 90 water conduit 17 is connected to the upper side of the casing 10, and has the outlet 95 opening 18 which registers with the opening 19 of the casing. A gate 20 is mounted in the conduit for controlling the flow of water therethrough. The upper end of the channel 16 is closed by the wall 25, so that the water which issues from the conduit will be directed against the blades of the wheel. It will be noted that the lower end of the channel 16 is open to readily permit the 100 free discharge of the water which has passed through said groove and driven the wheel around. The portion of the casing opposite that in which the channel 16 is formed, is open, so that there is no frictional contact 105 between the wheel and that side of the casing. Thus the wheel only frictionally con-

tacts with one side of the casing, thereby reducing the friction by one-half.

It will thus be seen that when the water is permitted to flow from the conduit into the casing, it will engage against the blade which is extended out into the channel 16. The force of the water will cause the wheel to rotate, as will be seen. As the wheel rotates the ends 28 will engage in the guide 33 whereby the blades will be turned into their inoperative positions within the grooves 28'. As the ends 27 successively engage with the pin 29' the blades will be turned to extend into the channel 16 of the casing in position to receive the stream of water thereagainst. The blades are so disposed around the wheel that two of them are under pressure of the water at the same time, while the remaining blades are in their inoperative position against the peripheral face of the body of the wheel.

Thus, by reason of the fact that there is used a casing which is practically one-half of the size of devices heretofore, a great economy of material is practised, the cost being greatly reduced, and friction reduced to a minimum.

What is claimed is:

1. A water motor including a segmental casing having a channel therein, a flanged rotor movable within the said channel, swingable blades carried by the rotor, means on one side of the casing for engagement

with the blades to turn said blades into extended operative position, and means on the other side of the casing for engagement with the blades to turn said blades into inoperative position.

2. A water motor including a segmental casing, a rotor mounted for partial engagement within the casing, the rotor having parallel peripheral radial flanges, the periphery of the body of the rotor between the flanges being formed with recesses, a blade pivotally mounted in each recess and having one end movable into and out of said recess, the other end of the blade being movable into and out of position across the casing, the ends of the pivotal portion of the blades being extended at right angles to the pivot and at right angles to each other, the casing being formed at one side with curved channel for engagement therein of the ends of the said pivots, to turn the blades into operative position, and a projection on the other side of the casing for engagement by and movement of the other ends of the said pivots to turn the blades into inoperative position.

In testimony whereof, I affix my signature, in the presence of two witnesses.

CHARLES LE DUC.
